UNITED STATES PATENT OFFICE.

CHARLES H. NITSCH AND THEODORE A. FEDERWITZ, OF PHILADELPHIA, PENNSYLVANIA, ASSIGNORS TO STOKES AND SMITH COMPANY, OF PHILADELPHIA, PENNSYLVANIA, A CORPORATION OF PENNSYLVANIA.

BOX-COVERING MACHINE.

Application filed May 10, 1923. Serial No. 638,116.

To all whom it may concern:

Be it known that we, CHARLES H. NITSCH and THEODORE A. FEDERWITZ, citizens of the United States, residing in the city and county of Philadelphia, State of Pennsylvania, have invented certain new and useful Improvements in Box-Covering Machines, of which the following is a specification.

Our invention relates to machines for covering previously formed or stayed boxes and their covers by applying thereto a cover blank, or for forming a box blank into box form and applying a cover blank serving both to hold the box blank elements in box-forming position and to cover the box.

In accordance with our invention, there are provided slides, units or slide units adjustable upon slides or guides to different positions with respect to the work-carrying structure to accommodate boxes or box covers of various sizes, each slide, unit or slide unit itself comprising or including cam structure for effecting in predetermined sequence and time relation movements of the individual structures carrying and actuating such tools or elements as brushes, rollers, corner lap fingers, edge turn-in fingers, pressure blocks and the like, or their equivalents.

It is a feature of our invention the aforesaid units and their tools may be utilized for applying wrappers or covering materials not only to simple or plain boxes and box covers but also to boxes and box covers having extension edges.

Further in accordance with our invention, there are formed novel adjustable cushioning or resiliently yielding means for and co-acting with the cover-applying rollers.

Further in accordance with our invention, there is provided novel structure embodying corner lap fingers for applying to the ends of the box the extensions on the side covering flaps of the blank.

Further in accordance with our invention, there is provided novel structure for effecting yielding or cushioned uniform pressure upon the work by the pressure blocks.

Our invention resides in the structures and structural features and combinations hereinafter described and claimed.

For an illustration of some of the various forms our apparatus may take, reference is to be had to the accompanying drawings, in which:

Fig. 1 is a side elevational view, partially in section, showing an assembly of three of the slides or units, the fourth being omitted for clearness.

Fig. 2 is a plan view of an assembly of the four slides or slide units for applying the cover blank to the sides and ends of the box.

Fig. 3 is a vertical sectional view, parts in elevation, of one of the slides or units provided with tools for applying the covering blank to the sides of a box.

Fig. 4 is a vertical sectional view, parts in elevation, of a modification of the structure of Fig. 3.

Fig. 5 is a vertical sectional view, parts in elevation, of a slide or slide unit provided with instrumentalities for applying a cover blank to the ends of the box.

Fig. 6 is a fragmentary plan view of a roller and its support.

Fig. 7 is an end elevational view, partly in section, on the line 7—7 of Fig. 6.

Fig. 8 is a plan view, partly in horizontal section, of the pressure block and its actuating and supporting plate.

Fig. 9 is a side elevation of the structure shown in Fig. 8.

Fig. 10 is a fragmentary plan view of the corner lap fingers and their supporting and actuating plate.

Fig. 11 is an end elevational view of the structure shown in Fig. 10.

Fig. 12 is a fragmentary plan view of the turn-in finger and its supporting and actuating plate.

Fig. 13 is an end elevational view of the structure shown in Fig. 12.

Fig. 14 is a development of the several cams indicating the directions and timing of the several movements controlled thereby.

Referring to Figs. 1 and 2, there is shown an assembly of the slides, units or slide units, 1 and 2, the units 1, 1 being disposed opposite each other in co-operative relation with the sides of the box B, and the units or

slides 2, 2 being disposed opposite each other and in co-operative relation with the ends of the box B.

The units 1 and 2 are mounted upon any suitable support, as the base or table 3, provided with slide or guide ways 4^a upon which rest and slide the laterally projecting members 4 upon the units 1 and 2, which are slidable or adjustable toward or away from the center of the structure or machine for accommodation of boxes of different sizes and proportions as regards length of sides and ends. Any suitable means, not shown, are provided for clamping the units to the base or table 3 in their adjusted or predetermined positions.

The units 1 and 2 are grouped around the platen 5 upon which the box and its cover blank engage, the platen being supported by a vertical column or plunger 6 movable vertically within the cylinder or housing 7, in which is disposed a spring 8 opposing downward movement of the platen 5 and restoring it to the normal position indicated in Fig. 1 upon completion of a cycle of operations. Disposed above the platen 5 is the form block or form plunger comprising the main form block 9 and the separate supplemental or auxiliary form block 10, the members 9 and 10 partaking of vertical movements in unison with and independently of each other, such movements having extents determined and timed by any suitable structure, as, for example, by cam structure, such, for example, as mechanism A of Letters Patent No. 691,329, or any equivalent structure, the members 9 and 10 corresponding, respectively, with the members 49 and 50 of said Letters Patent.

Referring to Fig. 3, a unit 1 comprises the housing or casing members 11, within which is disposed the cam barrel or cylinder 12, rotatable in bearings 13, 13, and having secured thereto at one end the gear 14 meshing with and driven by the gear 15, meshing with and driven by the long gear or pinion 16 secured upon the shaft 17, which extends across to the opposite unit 1 where there is secured thereon a similar elongated pinion or gear 16 driving the gear 15 of the second unit 1. As indicated in Fig. 2, the shaft 17 is driven by the bevel gear 18, secured thereto, driven by the bevel gear 19, secured upon shaft 20 and driven by the bevel gear 21, in turn driven by the bevel gear 22, secured upon the vertical shaft 23, which latter is driven by any source of power, which also drives the cam or equivalent structure which actuates the members 9 and 10.

The gear 15 is secured upon and rotates the second cam barrel or cylinder 24 disposed within the casing 1 and having bearings at 25, 25. The cam barrel 12 is provided with the circumferentially continua-

ous cam grooves or slots 26 and 27, each having portions disposed at different distances longitudinally of the axis of rotation. Disposed in the groove 26 is the roller or cam follower 28, disposed upon the pin or stub shaft 29, secured in the plate or frame 30 sliding and guided upon the casing or housing 11 for preferably rectilinear movement parallel to the axis of rotation of the cam barrel 12.

Carried by the frame or plate 30 at its forward end is the transversely extending support or member 31, which is provided at its opposite ends, as indicated in Figs. 3, 6 and 7, with the bearing supports 32, within each of which is disposed the shaft 33 between a shoulder on which and the end of the recess or chamber in the member 32 is disposed the helical spring 34, which is maintained under suitable degree of compression by adjustment of the nut 35, threaded upon shaft 33, and locked by nut 36, adjustment of nuts 35 serving to align roller 40. The spring 34 serves as a cushion resiliently opposing inward movement of the shaft 33. At its outer or forward end the shaft 33 carries the bearing member 37, in which rotates the shaft 38, on which is secured the cylinder 39, upon which is mounted the roller 40, of any suitable material, either rigid or yielding. Carried by the member 31, and therefore by the frame or plate 30, is the bar 41 carrying the numerous spreader brush units 42 disposed above the roller 40 in arcuate alignment, their outer ends in arcuate alignment, the different brush units having different lengths at different positions longitudinally of the bar 41, which latter is pivoted at 43 in the brackets 44 carried by the member 31.

Disposed in the second groove or slot 27 of the cam barrel 12 is the roller or cam follower 45 carried upon the pin or stub shaft 46 carried by the second frame or plate 47, which is movable preferably in rectilinear path parallel to the axis of rotation of the cam barrel 12, upon slides or guides on the housing 11.

As indicated in Figs. 3, 10 and 11, the frame 47 carries at its forward end the transversely extending bar 48, adjustable longitudinally of which are the bracket members 49, which may be secured in any suitable position upon the bar 48 by the set screws 50. Each of the brackets 49 carries the vertical pivot pin or shaft 51, upon which is pivoted the bracket 52, to which is clamped, by clamping member 53 held by screw 54, the corner lap finger 55 having at its forward end the vertically extending rounded ribs 56 for engaging the extensions on the side flaps of the cover blank for lapping said extensions around the corners of the box into engagement

with the ends thereof, suitable pressure being applied to each finger 55 by a spring 57, Fig. 11 wrapped around the pivot 51 and engaging at its opposite ends with the brackets 49 and 52, respectively.

The second cam barrel or cylinder 24 of the unit 1 has the cam slots or grooves 58 and 59. Disposed in the cam groove 58 is the roller or cam follower 60, carried upon the pin or stub shaft 61 carried by the frame or support 62 movable preferably in a rectilinear path parallel to the axis of rotation of the cam barrel 24 upon the slide or guide ways on the casing 11. Carried upon the forward end of the frame 62 is the transversely extending bar or support 63, Figs. 3, 12 and 13, to which is secured by screw 64 a clamping member 65, between which and the member 63 is clamped the plate or turn-in finger 66.

In the cam slot 59 is disposed the roller or cam follower 67 carried by a pin or stub shaft 68, carried by the support or frame 69, movable preferably in a rectilinear path parallel to the axis of rotation of the cam barrel 24 upon the slide or guide ways on the casing 11. At its forward end the frame 69 is provided with holes 70, in which are supported and longitudinally movable the pins 71 secured to and supporting the transversely extending bar 72 upon the frame 69. Springs 73, attached at their forward ends to the pins 71 and at their rear ends to the plate 69, exert a pull upon the bar 72, holding it against the abutments or stops 74, 74 at the forward ends of rods 75, whose forward portions are of sufficiently small diameter freely to pass through the interiorly threaded sleeves or nuts 76, into which thread the rear portions 77 of the rods 75. Surrounding the rods 77 are the helical springs 78, which with the nuts or sleeves 76 are disposed in recesses in the sides of the frame 69. Each rod 77 has at its rear end a head 79 for application of a spanner or wrench for rotating the rods 77. By rotating the rod 77, it threads further into or outwardly from its nut or sleeve 76, thereby advancing or withdrawing the stop 74 at the forward end of its forward portion 75. By these means each of the stops or abutments 74 is adjustable independently of the other without, however, affecting the spring 78, whereby all the springs 78, notwithstanding different adjustments of the stops 74, exert equal forces in opposition to the rearward thrust of the member 72.

The bar 72 is slotted, as indicated in Fig. 3, and in the slot is disposed the pressure bar or block 80, held in any desired position by clamping screws 81. The pressure bar or block 80 has upon its front face a pad 82, of felt or any other suitable material. The pressure blocks, when the frame 69 is moved forwardly toward the box, engages

the box, and the pressure is transmitted backwardly through the bar 72 and the stops 74 and rods 75 to the springs 78, the aforesaid adjustment of the stops 74 serving to ensure application of uniform pressure by the pressure block throughout its area of engagement with the box.

Referring to Fig. 4, there is shown a modified or substitute form of unit for effecting the functions described in connection with Fig. 3. In this instance, in lieu of the two cam barrels of Fig. 3, there is utilized a single cam barrel 12^a, rotatable upon suitable bearing structure 13^a, and having the four cam slots or grooves 26, 27, 58 and 59, with which, as before, co-act the rollers or cam followers 28, 45, 60 and 67, respectively, for effecting the timed forward and return movements of the frames 30, 47, 62 and 69, respectively. In this case, however, the frames or supports 30 and 47 are disposed above and the frames or supports 62 and 69 are disposed below the cam member 12^a, which latter is driven by the gear 14, secured thereto, such gear meshing with the elongated gear or pinion 16, as gear 15, Fig. 3, meshes with gear 16.

Referring to Figs. 1, 2 and 5, the slides, units or slide units 2, for applying the cover blanks to the ends of the box, are in general similar to the units 1 hereinbefore described. Each comprises a cam barrel or cylinder 12^b having bearings at 13^b in the housing or casing 11 and having secured thereto the driving gear 14 meshing with and driven by the elongated gear or pinion 16^a, secured upon and driven by the shaft 17^a which extends across to the opposite unit 2, where it carries a second gear 16^a driving the gear 14 of the second unit 2. As indicated in Figs. 1 and 2, one of the elongated gears 16^a has a bevel gear on one end thereof which is driven by the bevel gear 22^a secured upon and driven by the vertical shaft 23^a, which is driven by the same source of power which drives the shaft 23 and the cam mechanism which operates the plungers 9 and 10.

The cam barrel 12^b is provided with the three cam slots or grooves 26^a, 58 and 59, with which co-act, respectively, the rollers or cam followers 28, 60 and 67 for actuating and controlling, respectively, the frames 30, 62 and 69, the three frames or supports being in this instance all located upon the same side of the cam barrel 12^b. As before, the frame 31 carries the brushes 42 and roller 40; the frame 62 carries the turn-in fingers 66, and the frame 69 carries the pressure block 80.

As indicated in Fig. 5, the mounting of the roller 40 and brushes 42 upon the frame 30 is in some respects different from the mounting of these members upon the frames 30 of Figs. 3 and 4. In the present instance,

there is pivoted at 83, at opposite sides of the front end of the frame 30, the transversely extending member 31 which, as before, is provided at its ends with the chamfered members 32 carrying the members 37, in which the roller 40 has bearings. The pivotal structure described permits rotation of the roller 40 and brushes 42 about the pivots 83 to position away from their normal position to permit access from above to the members 66 and 80, below, and their associated parts.

Referring to Fig. 14, there are shown developments of the cam slots for one complete circumference or one complete revolution of each of the cams, all the cams whose slots are shown preferably making one complete revolution in the same period of time and the changes in direction and displacements of the cam slots being timed in substantially the relations indicated in Fig. 14, it being understood, however, that any other equivalent arrangement may be employed, as may be found suitable or desirable.

In Fig. 14, distances horizontally represent time; while distances vertically indicate the departures or extents of movement of the various frames 30, 47, 62 and 69, and the main and auxiliary plungers or form blocks 9 and 10, it being understood, however, that Fig. 14 is merely illustrative and that the relative timings and the relative extents of departure and movements of the frames and plungers may be otherwise proportioned.

In Fig. 14, the developed cam slots are indicated at 26, 26^a, 27, 58, 59, 84 and 85. The line 26, indicating cam slots 26 of the units 1, shows the timing of the forward and return movements of the rollers 40 and brushes 42, which apply the wrapper or cover blank to the sides of the box. Line 27 indicates cam slots 27 of units 1, and shows the timing of the forward and return movements of the corner lap fingers 55 as effected by the units 1. Line 26^a, indicating cam slot 26^a of units 2, shows the forward and return movements of the rolls 40 and brushes 42 which apply the wrapper or cover blank to the ends of the box. Line 58, indicating cam slots 58 of units 1 and 2, shows the forward and return movements of the turn-in fingers 66 operating both at the sides and ends of the box. Line 59, indicating cam slots 59 of units 1 and 2, shows the forward and return movements of the pressure blocks 80, which apply pressure to the wrapper or cover blank both to the sides and ends of the box. The line 84 indicates the relative descent and return movements and their timing of the main plunger or form block 9, and the line 85 indicates the corresponding movements and their timing of the auxiliary or associated plunger or form block 10.

The operation is as follows:

Assuming the box (or box cover) to have been previously formed, that is, assuming that the apparatus is to perform no operation regarding the formation or staying of the box itself, the box is placed in proper register with and upon the cover or wrapper blank, having adhesive, as glue or equivalent, upon one side thereof. The box with the wrapper or cover blank adhering to its bottom is placed upon the form block structure, 9, 10, the plungers 9 and 10 being in the relation indicated in Fig. 1 at or approximate the upper end of their vertical travel. The plungers 9 and 10, carrying the box and the wrapper or cover adhering to its bottom, then descend, the box and wrapper engaging upon the upper surface of the platen 5, which yields and descends in opposition to spring 8 as the members 9 and 10 descend. During the initial downward movements of the plungers 9 and 10, as indicated by the inclined portions *a*, *a* of lines 84 and 85, Fig. 14, the box and cover are forced downwardly past the brushes 42 and rollers 40 of the units 1, which have advanced the brushes and rollers, as indicated by portion *a* of line 26, Fig. 14, to position to cause the brushes to fold the side flaps of the cover blank upwardly into engagement with the sides of the box, the descending box passing the side rollers 40 immediately after passing the brushes, the rollers forcing the cover into intimate contact with the sides of the box, where it adheres because of the previous application of adhesive to the cover blank as a whole. The box then comes to rest in position opposite the corner lap fingers 55 of units 1, the rest period being indicated by the portions *b* of lines 84 and 85, Fig. 14. During this period of rest, the fingers 55 are advanced by the cam slots 27 of the units 1, as indicated by the portion *a* of line 27, the fingers 55 folding inwardly along the ends of the box the extensions on the side flaps of the cover blank, the springs 57 exerting pressure through the fingers 55 upon the extensions, causing them to adhere to the ends of the box. The fingers 55 remain in their advanced position, for the time indicated by the portion *b* of line 27, Fig. 14. While the fingers 55 are advancing, as aforesaid, the end brushes 42 and end rolls 40 are advanced by cam slots 26^a of the units 2, these end brushes and rolls being disposed vertically below the corner lap fingers 55, as indicated in Fig. 1, these end brushes and rolls being advanced during the time indicated by the portion *a* of line 26^a, Fig. 14, and remaining in their fully advanced position for the time *b* indicated on said line 26^a. The auxiliary plunger 10 recedes or rises slightly, as indicated by portion *c* of line 85, separating from the main plunger 9, which during the time *c*,

line 84, descends further, and during this period forces the box and cover downwardly past the end brushes 42 and end rolls 40 which, as aforesaid, have been previously advanced, this action applying to the ends of the box or end flaps of the cover blank in position overlying the aforesaid extensions on the side flaps which have been turned in by the corner lap fingers 55. The auxiliary plunger 10 remains in the position to which it has receded for the time indicated by the portion *d* of line 85. After the downward movement indicated by the portion *c* of line 84, the plunger 9 comes to rest for the period indicated by the portion *d* of line 84, during which time the cam slots 58 in the four units 1 and 2 advance the turn-in fingers 66 during the time indicated by the portion *a* of line 58, and immediately recede to normal position during the time indicated by the portion *b* of said line 58. This causes a quick advance of the turn-in fingers 66 at both sides and both ends of the box, folding the side and end flaps of the cover blank, which have been projecting above the upper edge of the box, to horizontal position, corresponding with the under side of the fingers 66 indicated in dotted lines in Figs. 3, 4 and 5, this action occurring while the auxiliary plunger 10 is spaced above the main plunger 9, the fingers 66 passing between the plungers 9 and 10 for this operation. As the fingers 66 are advanced, the pressure blocks 80 are advanced during the time represented by the portion *a* of line 59, Fig. 14, by the four cam slots 59 in the four units 1 and 2, into light engagement with the sides and ends of the box for a period represented by the portion *b* of the aforesaid line 59. The corner lap fingers 55 have remained advanced during substantially these last named operations as indicated by the portion *b* of the aforesaid line 27, the downward movement of the box during these periods causing a wiping of the fingers 55 upon the ends of the box as it descends past them into co-action with the end brushes and rollers 42 and 40. The corner lap fingers 55 are eventually returned to normal position at and during the time indicated by the portion *c* of the aforesaid line 27. After the turn-in fingers 66 have advanced and are returning, the auxiliary plunger 10 again descends during the period indicated by the portion *e* of the aforesaid line 85 to the position and for the time indicated by the portion *f* of said line 85, in so doing folding the ends of the side and end flaps of the cover blank from horizontal position, to which moved by the turn-in fingers 66, downwardly to vertical position in contact with the inner surfaces of the vertical sides and ends of the box, the auxiliary plunger 10 in moving as aforesaid again coming into contact or close relation with the main plunger 9, which descends further during the time indicated by the portion *e* of the aforesaid line 84 to the position and for the time indicated by the portion *f* of said line, the pressure blocks 80 being advanced through the periods represented by *d*, *e* and *f* of line 84, the pressure blocks, however, receding slightly during the period indicated by the portion *e* of the aforesaid line 59 to position and for the time corresponding with the portion *d* of said line, whereafter they are again advanced during the time indicated by the portion *e* to the position and for the time indicated by the portion *f*, and during this time they are further in advance than during the period represented by the portion *b* of said line 59, exerting correspondingly greater pressure upon the sides and ends of the box and then returning to normal position during the time represented by the portion *g* of said line 59. The application of the wrapper or cover to the box is now completed, all of the brushes 42, rollers 40, corner lap fingers 55, turn-in fingers 66 and pressure blocks 80 having returned to their normal positions. At the ends of the periods *f*, *f*, lines 84 and 85, the main and auxiliary plungers 9 and 10 return or ascend during the periods indicated by the portions *g*, *g* of said lines 84 and 85 to their uppermost or starting positions, suitable mechanism stripping the finished box from the plungers during their return movement, as well understood in the art, the box when stripped from the plungers being then kicked off from the platen 23 into a chute or other suitable receptacle, the platen 5 rising to its normal position indicated in Fig. 1 upon upward return movement of the plungers 9 and 10.

Apparatus of the character described may be utilized also for simultaneously forming a box from a box blank and applying the wrapper or cover. A box blank, comprising a body portion with side and end flaps, may be placed in register with the cover blank, coated with adhesive, and the sides and ends of the box may be folded upwardly to their final and vertical positions, the application of the wrapper or cover serving to stay them and hold the box blank in box formation.

As well understood in this art, when the box or box cover is of that type having an extension edge, there may be used, in lieu of each of the simple or plain rollers 40 as hereinbefore described, that type of roller having a recess of such form and in such position as to apply the wrapper or cover upon the extension edge of the box; and the spreader brushes 42 are in such case omitted. It accordingly will be understood that in place of the simple or plain rollers 40, and brushes 42, carried by the frames

30, as hereinbefore described, those frames will carry rollers of the type suitable for applying the wrapper or cover material to the extension edge of the box; or any 5 equivalent mechanism may be employed.

For the sake of brevity in the appended 10 claims, the term "tool" is generic to any instrument which operates upon, actuates or controls the cover or wrapper, or any 15 portion thereof, or the box or any part thereof, and includes any of the herein described brushes, rollers, corner lap fingers, turn-in fingers, and pressure blocks, and their equivalents.

15 What we claim is:

1. In a box-covering machine, the combination with a support, of a unit adjustable to different positions thereon for operation upon boxes of different dimensions, said 20 unit comprising cam structure, a tool controlled thereby, and means for rotating said cam structure always in one direction.

2. In a box-covering machine, the combination with a support, of a unit adjustable to different positions thereon for operation 25 upon boxes of different dimensions, said unit comprising cam structure rotating always in one direction, and a tool positively advanced by said cam.

3. In a box covering machine, the combination with a support, of a unit adjustable to different positions thereon for operation upon boxes of different dimensions, said unit comprising cam structure, and a 35 tool positively returned from operative position thereby.

4. In a box-covering machine, the combination with a support, of a unit adjustable to different positions thereon for operation 40 upon boxes of different dimensions, said unit comprising cam structure, and a tool positively advanced and returned thereby.

5. In a box-covering machine, the combination with a support, of a unit for each 45 of a plurality of faces of the box, said units being individually adjustable upon said support for operation upon boxes of different dimensions, each of said units comprising cam structure, and a tool controlled thereby, and means common to said cam structures for rotating them always in one direction.

6. In a box-covering machine, the combination with a support, of a pair of units 55 adjustable upon said support for operation upon boxes of different dimensions, each of said units comprising cam structure rotating always in one direction and a tool positively advanced and returned thereby, and means common to said units for driving the cam structures thereof.

7. In a box covering machine, the combination with a support, of a pair of units 60 adjustable upon said support for operation

upon boxes of different dimensions, each of said units comprising cam structure and a tool controlled thereby, a gear secured to each of said cam structures, elongated gears driving said gears and along which said 70 gears are adjustable upon adjustment of said units, and a common driving shaft for said elongated gears.

8. In a box-covering machine, a tool operating unit comprising rotary cam structure, a tool controlled thereby, a gear secured to said cam structure, and an elongated gear meshing with said gear and along which said gear is adjustable.

9. In a box-covering machine, a tool operating unit comprising rotary cam structure, a tool controller thereby, a gear secured to said cam structure, and an elongated gear meshing with said gear and along which said unit with its gear is adjustable.

10. In a box-covering machine, the combination with a support, of a tool operating unit adjustable to different positions thereon and comprising a rotatable cam barrel 90 having a cam slot, a cam follower engaging in said slot, a frame actuated by said cam follower, and a tool carried by said frame.

11. In a box-covering machine, a tool operating unit comprising a rotatable cam barrel having a cam slot, a cam follower engaging in said slot, a frame actuated by said cam follower in a path substantially parallel to the axis of rotation of said cam barrel, and a tool carried by said frame.

12. In a box-covering machine, the combination with a support, of a tool operating unit adjustable to different positions thereon and comprising a rotatable cam barrel having a cam slot, a cam follower engaging in said slot, a frame actuated by said cam follower, a tool carried by said frame, and a common support for said cam barrel and frame.

13. In a box-covering machine, a tool operating unit comprising a rotatable cam barrel having a cam slot, a cam follower engaging in said slot, a frame actuated by said cam follower, a tool carried by said frame, and a housing for said cam barrel, said frame projecting to the exterior of said housing.

14. In a box-covering machine, a tool operating unit comprising a rotatable cam barrel having a cam slot, a cam follower engaging in said slot, a frame actuated by said cam follower, a tool carried by said frame, and a housing for said cam barrel, said frame projecting to the exterior of said housing and sliding thereon.

15. In a box-covering machine, a tool operating unit comprising a rotatable cam barrel having a cam slot, a cam follower engaging in said slot, a frame actuated by said cam follower, a tool carried by said frame,

5 a housing for said cam barrel, said frame projecting to the exterior of said housing, a gear secured to said cam barrel, and a driving gear exterior to said housing driving said first named gear.

10 16. In a box-covering machine, a tool operating unit comprising a rotatable cam barrel having a cam slot, a cam follower engaging in said slot, a frame actuated by said cam follower, a tool carried by said frame, a housing for said cam barrel, said frame projecting to the exterior of said housing, a gear secured to said cam barrel and extending to the exterior of said housing, and an 15 elongated gear on the exterior of said housing driving said first named gear and along which said unit is adjustable.

20 17. In a box-covering machine, the combination with a support, of a tool operating unit adjustable to different positions thereon and comprising a cam barrel having a plurality of cam slots, a cam follower in each of said slots, a plurality of frames actuated by said cam followers and disposed 25 upon the same side of said cam barrel, and a tool carried by each of said frames.

30 18. In a box-covering machine, the combination with a support, of a tool operating unit adjustable to different positions thereon and comprising a cam barrel having a plurality of cam slots, a cam follower in each of said slots, a plurality of frames actuated by said cam followers and disposed upon opposite sides of said cam barrel, and 35 a tool carried by each of said frames.

40 19. In a box-covering machine, a tool operating unit comprising a cam barrel having a plurality of cam slots, a cam follower in each of said slots, a plurality of frames actuated by said cam followers and disposed upon the same side of said cam barrel, and a tool carried by each of said frames, said frames having paths of movement substantially parallel with the axis of rotation of 45 said cam barrel.

50 20. In a box-covering machine, a tool operating unit comprising a cam barrel having a plurality of cam slots, a cam follower in each of said slots, a plurality of frames actuated by said cam followers and disposed upon opposite sides of said cam barrel, and a tool carried by each of said frames, said frames having paths of movement substantially parallel with the axis of rotation of 55 said cam barrel.

60 21. In a box-covering machine, a tool operating unit comprising a rotary cam, a cam follower co-acting therewith, a frame slideable by said cam follower substantially parallel to the axis of rotation of said cam, and a corner lap finger pivoted to said frame for movement about an axis normal to the plane of movement of said frame.

65 22. In a box-covering machine, a tool operating unit comprising a plurality of cams

rotatable as a unit, a cam follower co-acting with each of said cams, frames actuated by said cam followers and movable in paths parallel with the axis of rotation of said cams, brush structure carried by one of said frames, and corner lapping finger structure carried by another of said frames.

70 23. In a box-covering machine, a tool operating unit comprising a plurality of cams rotatable as a unit, a cam follower co-acting with each of said cams, frames actuated by said cam followers and movable in paths parallel with the axis of rotation of said cams, roller structure carried by one of said frames, and corner lapping finger structure 80 carried by another of said frames.

75 24. In a box-covering machine, a tool operating unit comprising a plurality of cams rotatable as a unit, a cam follower co-acting with each of said cams, frames actuated by 85 said cam followers and movable in paths parallel with the axis of rotation of said cams, brush and roller structures carried by one of said frames, and corner lapping finger structure carried by another of said frames.

90 25. In a box-covering machine, a tool operating unit comprising a plurality of cams rotatable as a unit, a cam follower co-acting with each of said cams, frames actuated by 95 said cam followers and movable in paths parallel with the axis of rotation of said cams, and turn-in finger and pressure block structures carried by different of said frames.

100 26. In a box-covering machine, a tool operating unit comprising a plurality of cams rotatable as a unit, a cam follower co-acting with each of said cams, frames actuated by 105 said cam followers and movable in paths parallel with the axis of rotation of said cams, and corner lapping finger and turn-in finger structures carried by different of said frames.

110 27. In a box-covering machine, a tool operating unit comprising a plurality of cams rotatable as a unit, a cam follower co-acting with each of said cams, frames actuated by said cam followers and movable in paths parallel with the axis of rotation of said cams, brush and roller structures carried by one of said frames, and turn-in finger and pressure block structures carried, respectively, by different of 115 others of said frames.

120 28. In a box-covering machine, the combination with a support, of a unit adjustable to different positions thereon, said unit comprising a cam structure rotating always in one direction, and a plurality of tools forwardly actuated at different times by said cam structure.

125 29. In a box-covering machine, the combination with a support, of a unit adjustable to different positions thereon, said unit 130

comprising a cam structure rotating always in one direction, and a plurality of tools positively advanced and returned at different times by said cam structure.

5. 30. In a box-covering machine, the combination with a support, of a unit adjustable to different positions thereon, said unit comprising a cam structure rotatable continuously in one direction and having a plurality of cam surfaces, and a plurality of tools forwardly actuated at different times by the respective cam surfaces.

15. 31. In a box-covering machine, the combination with a support, of a unit adjustable to different positions thereon, said unit comprising a cam structure rotatable continuously in one direction and having a plurality of cam surfaces, and a plurality of tools positively advanced and returned at different times by the respective cam surfaces.

25. 32. In a box-covering machine, the combination with a support, of a unit adjustable to different positions theron, said unit comprising a rotatable cam barrel having a plurality of cam slots disposed in different positions longitudinally of the axis of rotation, a plurality of tools, and followers engaging in said slots for positively advancing said tools at different times.

30. 33. In a box-covering machine, the combination with a support, of a unit adjustable to different positions thereon, said unit comprising a rotatable cam barrel having a plurality of cam slots disposed in different positions longitudinally of the axis of rotation, a plurality of tools, and followers engaging in said slots for positively advancing and returning said tools at different times.

35. 34. In a box-covering machine, the combination with a support, of a unit adjustable to different positions thereon, said unit comprising a rotatable cam structure, a tool support positively actuated by said cam structure in a direction parallel with the axis of rotation of said cam structure, and a tool carried by said tool support.

40. 35. In a box-covering machine, the combination with a support, of a unit adjustable to different positions thereon, said unit comprising a rotatable cam structure, a tool support positively actuated by said cam structure in a direction parallel with the axis of rotation of said cam structure, and a box-engaging roller carried by said tool support and rotatable about an axis fixed in position with respect to said tool support.

45. 36. In a box-covering machine, the combination with a support, of a unit adjustable to different positions thereon, said unit comprising a rotatable cam structure, a tool support positively actuated by said cam structure in a direction parallel with the

axis of rotation of said cam structure, and a box-engaging roller carried by said tool support and rotatable about an axis fixed in position with respect to said tool support and extending at right angles to the axis of rotation of said cam structure.

50. 37. In a box-covering machine, the combination with a movable frame, of a member carried by and movable with respect to said frame, a tool carried by said member, and an adjustable stop structure for said member comprising a nut, and a rod threaded in said nut and projecting beyond said nut to form a stop for said member.

55. 38. In a box-covering machine, the combination with a movable frame, of a member carried by and movable with respect to said frame, a tool carried by said member, and adjustable stop structure for said member comprising a nut, and a rod threaded in said nut and projecting beyond said nut to form a stop for said member, said nut detached from and thrusting against said frame, and a spring engaging said frame and nut and opposing the movement of said member and said stop.

60. 39. In a box-covering machine, the combination with a movable frame, of a member carried by said frame and movable with respect thereto, a pressure block carried by said member, a plurality of rods spaced from each other and carried by said frame, ends of said rods forming stops for said member, said rods movable longitudinally with respect to said frame, a nut threaded on each of said rods and disposed in detached relation to said frame and abutting against said frame, and a spring confined between said nut and said frame to oppose movement of said pressure block.

65. 40. In a box-covering machine, the combination with a movable frame, of a member yieldingly mounted upon said frame, said member having a slot, a pressure block engaging in said slot and carried by said member, and a cam for actuating said frame.

70. 41. In a box-covering machine, the combination with a support, of a unit adjustable to different positions thereon, said unit comprising cam structure, a tool controlled thereby, and a gear for rotating said cam structure always in one direction, driving means for said gear, and an adjustable driving connection between said means and said gear through which said gear is driven for all positions of said unit.

75. 42. In a box-covering machine, the combination with a support, of a plurality of units adjustable on said support for operation upon boxes of different dimensions, each of said units comprising cam structure, a tool controlled thereby, and a gear for driving said cam structure, means common to said gears for driving them, and an ad-

- justable driving connection between said means and each of said gears for driving said gears in all positions of said units.
43. In a box-covering machine, the combination with a support, of a unit adjustable to different positions thereon and comprising a cam structure, and a corner lap member actuated thereby.
44. In a box-covering machine, the combination with a support, of a unit adjustable to different positions thereon and comprising cam structure rotatable always in one direction, and a corner lap member actuated thereby.
45. In a box-covering machine, the combination with a support, of a unit adjustable to different positions thereon and comprising a housing, a plurality of cam structures carried by said housing and rotatable about different axes, means for driving said cam structures, and a tool actuated by each of said cam structures.
46. In a box-covering machine, the combination with a support, of a unit adjustable to different positions thereon and comprising a housing, a plurality of cam structures carried by said housing and rotatable about different axes, means for driving said cam structures in timed relation to each other, and a tool actuated by each of said cam structures.
47. In a box-covering machine, the combination with a support, of a unit adjustable to different positions thereon and comprising a housing, a plurality of cam structures carried by said housing and rotatable about different axes, a tool actuated by each of said cam structures, and means common to said cam structures for driving them.
48. In a box-covering machine, the combination with a support, of a unit adjustable to different positions thereon and comprising a housing, a plurality of cam structures carried by said housing and rotatable about different axes, a tool actuated by each of said cam structures, and means common to said cam structures for driving them, a driving member with respect to which said unit is adjustable, and an adjustable driving connection between said driving member and said driving means.
49. In a box-covering machine, the combination with a support, of a unit adjustable to different positions thereon and comprising a housing, a plurality of cam structures carried by said housing and rotatable about axes substantially parallel with each other, means for driving said cam structures, and a tool actuated by each of said cam structures.
50. In a box-covering machine, the combination with a support, of a unit adjustable to different positions thereon and comprising a housing, a plurality of cam structures carried by said housing and rotatable about axes substantially parallel with each other, a frame controlled by each of said cam structures and movable substantially parallel with the axis of rotation thereof, and a tool carried by each of said frames.
51. In a box-covering machine, the combination with a support, of a unit adjustable to different positions thereon and comprising a housing, a plurality of cam structures carried by said housing and rotatable about different axes, a corner lapping tool actuated by one of said cam structures, and a tool actuated by another of said cam structures.
52. In a box-covering machine, the combination with a support, of a pair of oppositely disposed units adjustable to different positions thereon and each comprising a plurality of cam structures rotatable about different axes, and a tool actuated by each of said cam structures, and a pair of oppositely disposed units adjustable to different positions on said support in directions at right angles to the directions of adjustment of said first named units, each of said last named units comprising a tool and actuating means therefor.
53. In a box-covering machine, the combination with a support, of a pair of oppositely disposed units adjustable to different positions thereon and each comprising a plurality of cam structures rotatable about different axes, a corner lapping tool actuated by one of said cam structures, and a tool actuated by another of said cam structures, and a pair of oppositely disposed units adjustable to different positions on said support in directions at right angles to the directions of adjustment of said first named units, each of said last named units comprising a tool and actuating means therefor.
- In testimony whereof we have hereunto affixed our signatures this eighth day of May, 1923.
- CHARLES H. NITSCH.
THEODORE A. FEDERWITZ.
